UNITED STATES PATENT OFFICE

131,372

DESIGN FOR A GOLF CLUB HEAD COVER

Alfred S. Reed, Ripon, Wis., and Clement J. Thelander, Chicago, Ill., assignors to Ripon Knitting Works, Ripon, Wis., a corporation of Wisconsin

Application November 9, 1940, Serial No. 96,446

Term of patent 7 years

To all whom it may concern:

Be it known that we, Alfred S. Reed and Clement J. Thelander, citizens of the United States, respectively residing at Ripon, in the county of Fond du Lac and State of Wisconsin, and Chicago, in the county of Cook and State of Illinois, have invented a new, original and ornamental Design for a Golf Club Head Cover, of which the following is a specification, reference being had to the accompanying drawing, forming a part thereof.

The figure is a perspective view of a golf club head cover, embodying our new design, the opposite side being of substantially the same appearance as the side shown.

The characteristic feature of the design resides in the golf club head cover shown having contrastingly colored boxing at the edge thereof as shown.

We claim:

The ornamental design for a golf club head cover, substantially as shown and described.

CLEMENT J. THELANDER.
ALFRED S. REED.
